ATTYS.

UNITED STATES PATENT OFFICE.

MAX ARNDT, OF AIX-LA-CHAPPELLE, GERMANY.

INDICATOR FOR CONTINUOUSLY REGISTERING THE MEAN WORKING PRESSURE.

No. 922,553.

Specification of Letters Patent.

Patented May 25, 1909.

Application filed September 26, 1905. Serial No. 280,175.

To all whom it may concern:

Be it known that I, MAX ARNDT, a subject of the King of Prussia, German Emperor, residing at the city of Aix-la-Chapelle, in the 5 Kingdom of Prussia, German Empire, have invented certain new and useful Improvements in Indicators for Continuously Registering the Mean Working Pressure; and I do hereby declare the following to be a full, 10 clear, and exact description of the invention, such as will enable others skilled in the art to which it appertains to make and use the same, reference being had to the accompanying drawings, and to letters or figures of reference marked thereon, which form a part of 15 this specification.

My present invention refers to an indicator by which the mean working pressure of an engine or the like may be continuously 20 registered.

In order that the invention may be clearly understood reference is made to the accompanying drawing in which—

Figure 1 is a sectional elevation and Fig. 2, 25 an elevation showing one form by way of example. Fig. 3 shows my invention applied to an engine.

The indicator consists of a funnel 1 arranged in the casing 5 having an outlet pipe 30 s^2 , and the funnel is fitted on a hollow part 3 having a bottom outlet 2; said hollow part turns around a pin 4 and has a second outlet 35 s^3 , the arrangement being such that the part of the medium received by the funnel can only escape by this outlet. A screen 6 is provided on the funnel 1 and protects the outlet s^3 from the medium contained in the casing 5.

To the side of the funnel 1 there is rigidly 40 attached the reversing pin 7, which passes freely through the wall of the casing 5 and is intermittently moved by a reciprocating dog 8 or the like, thereby moves the funnel alternately into the one and the other angular 45 position. The dog 8 is attached to a bevel wheel 9. This bevel wheel meshes with a second smaller bevel wheel 10, arranged, together with the driving pulley 12, on shaft 11.

The driving pulley 12 is turned in the following manner: The case D of the indicator is connected by means of its two stays a^1 , 50 and a^2 , and by means of the pipes r^1 and r^2 by the cocks z , z^1 , with the steam engine-cylinder C and is kept under constant water- 55 pressure H by the bridge u. The reversing of the intercepting-channel i, is accomplished

by means of the groove-wheel and its cord 13 which is hooked onto the bracket 13^b , which is stationary upon the piston-rod K, and, consequently, follows the motion of the machine-piston and which, in one dead-point of the crank of the machine, is in the position I (drawn in heavy lines), and, in the other dead-point, in the position II (drawn in dotted lines). (13^a, 13^c). The drawing-back 65 of cord 13 is done by means of spiral-spring 12^c, which is connected in 12^a with the rope-pulley 12, and in 12^b, with any part of the case S. In pulling the rope of the first position to the second position the spring 12^a, 70 is, therefore, bent, and in passing from the first position to the second it rolls up again.

The groove-wheel 12 is by the axis 11 firmly connected with the cone-wheel 10 which locks into the cone-wheel 9. The latter carries a cam 8 which receives an oscillating motion and thereby reverses the intercepting-channel 1 by means of the pin 7 once to one side, once to the other side every time the machine is shifted.

A small pillar 14 may be provided to carry the indicator.

The continuous indicator acts as follows: A medium which is to be measured, for example, water, enters at inlet m. The piston k 85 of the indicator is put under a load from either the one or the other side in proportion to the difference between pressures active at the moment in front and behind the piston of the engine to be indicated. These loads are 90 taken up by the measuring spring f and the resulting movements of the piston k of the indicator are transmitted by the piston rod h of the indicator to the slide d connected therewith, so that the latter alternately opens the 95 passage through the right or the left opening of the slide d in proportion to the working pressure active at the moment on one of the two sides of the piston k, thus an amount of driving medium corresponding to the difference of the pressures on the two sides of the piston can pass through the passage made by the slide. The driving medium enters through pipes i and i^1 . At the beginning of a stroke of the driving piston of the engine to 100 be indicated, the cord 13 is drawn to the outside by the bracket 13^b , and turns at the same time the wheel 12 and with it the axis 11 and the bevel gears 10 and 9, turn the dog 8, and the latter reverses the funnel 1 by means of 105 pin 7 in such a manner that the wall 1^a of the funnel stands under the middle of the pas-

sage e , and the amount of medium allowed by slide d to pass through the left side of the passage e can flow past the funnel 1 into the casing 5 and thence through outlet s^2 into a measuring device of any design. If now before the termination of the respective stroke of the engine piston corresponding to this position of the funnel 1 compression takes place in the cylinder of the engine, the piston k of the indicator will, under the action of the compression on its right side, be moved to the left, viz., the right side of the passage e is opened, and the medium now passing through will flow into funnel 1 and thence through outlet s^3 . At the very moment of the change of stroke, however, the funnel is suddenly reversed by the dog 8 which is turned back in the meantime in such a manner that now the other side of the funnel 1^b stands under the middle of the passage e ; thus the medium passing at the right through the passage e will no longer enter the funnel 1, but will flow off through the casing 5 and outlet s^2 . This continues until compression takes place on the other side of the engine piston, when the pressure on the left side of the indicator piston k again pushes the slide d to the right, and thereby opens the left side of the passage e ; now an amount of medium corresponding to the compression acting in front of the engine piston can flow into the funnel 1, until the latter is again suddenly reversed into the opposite position by means of the dog 8 at the end of the stroke of the engine piston, and the amount of medium corresponding to the mean working pressure of the engine piston again escapes through the outlet s^2 during the new stroke until the following

compression begins. The amount of medium thus escaping through s^2 corresponds with the mean acting working pressure behind the piston, and the amount caught by the funnel 1 and carried off through outlet s^3 corresponds to mean pressure in front of the piston of the engine.

45 I claim:

1. In an indicator for registering the mean pressures in cylinders, the combination of a casing having an outlet and an inlet, means for opening and closing said inlet adapted to permit and prevent liquid passing through the same, reciprocating means adapted to be operated by the pressures to be measured connected with the latter means, a funnel provided with an outlet under said inlet, and outlet means in said casing, and means actuated by said reciprocating means for oscillating said funnel, as set forth.

2. In an indicator for registering the mean pressures in cylinders, the combination of a casing having an outlet and an inlet, a slide valve for opening and closing said inlet, a cylinder having admission ports, a piston in said cylinder, a rod connecting said piston with said slide valve, a funnel provided with an outlet under said slide valve in said casing and means driven from said rod for oscillating said funnel, as set forth.

50 In testimony that I claim the foregoing as my invention, I have signed my name in presence of two subscribing witnesses.

60 MAX ARNDT.
